DESIGN FOR A TEXTILE FABRIC

John W. Lindsay, North Adams, Mass.

Application May 14, 1940, Serial No. 92,344

Term of patent 3½ years

to all whom it may concern:

Be it known that I, John W. Lindsay, a citizen of the United States, residing in North Adams, in the county of Berkshire and State of Massachusetts, have invented a new, original, and ornamental Design for a Textile Fabric, of which the following is a specification, reference being had to the accompanying drawing, forming part hereof.

Fig. 1 is a plan view of a textile fabric showing my design, and

Fig. 2 is the reverse side of a portion thereof.

I claim:

The ornamental design for a textile fabric, substantially as shown.

JOHN W. LINDSAY.
